UNITED STATES PATENT OFFICE.

WILLIAM M. PIPER, OF ALLEGHENY, PENNSYLVANIA, ASSIGNOR TO MARY S. CHALFANT, OF ALLEGHENY, PENNSYLVANIA.

DRAFT-RIGGING.

SPECIFICATION forming part of Letters Patent No. 717,615, dated January 6, 1903.

Application filed October 10, 1902. Serial No. 126,723. (No model.)

To all whom it may concern:

Be it known that I, WILLIAM M. PIPER, of Allegheny, Allegheny county, Pennsylvania, have invented a new and useful Draft-Rigging, of which the following is a full, clear, and exact description, reference being had to the accompanying drawings, forming part of this specification, in which—

Figure 1 is a top plan view, partly broken away, showing one form of my improved draft-rigging; and Fig. 2 is a similar view showing a modified form of the same.

My invention relates to draft-rigging wherein springs are combined with movable friction elements, and more especially to the wedge-and-spring system; and it is designed to improve the construction of such rigging and provide for more deflection than can be conveniently arranged for with the wedge-and-spring system alone; also, to provide for an easier action on a lighter strain, while on heavier strains the power will be furnished by the friction system.

In the drawings, referring to the form of Fig. 1, 2 2 represent the draft-timbers; 3, the draft-bar; 4, the yoke, and 5 5 the side irons and supports for the parts of the rigging. 6 is a rear follower, between which and a follower 7 are placed two spiral springs 8, which 30 may be held in place by inwardly-projecting stems 9 on one or both of the followers. In the front part of the rigging is a follower 10, having its body similar to the follower 7, each of these having on their inner ends oppositely-inclined faces 11, which act upon the opposite ends of oppositely-movable wedge-blocks 12 12. A spiral spring 13 is held between the wedge-blocks by stub 14, this spring normally pressing the wedge-blocks outwardly 40 and holding them in the position shown. In this position the front follower 10 rests against stops 15 on the draft-iron, and the rear follower 6 rests against similar rear stops 16.

In the operation of the rigging when a light pulling strain is brought upon the draw-bar 4, acting upon the rear follower 6, draws it forward, and thereby compresses the springs 8, and at the same time the follower 7 will be forced forwardly slightly under the pressure of these strains, moving in the wedge-blocks against the action of their friction on

the inclined surfaces. The action in buffing will be substantially the same, the follower 10 moving backwardly, and thus moving the wedge-blocks inwardly, while simultaneously 55 moving the follower 7 backwardly, thus compressing the two rear springs 8. An easy action is thus afforded, the major portion of which is borne by the springs 8. In heavier buffing or pulling strains the springs 8 will be 60 compressed until the rear follower strikes the stems 9, after which the further movement will be received by the friction wedge system, in which enough resisting power is afforded to carry the strains desired. 65

In Fig. 2 I show a form similar to that shown in Fig. 1, except that instead of allowing the springs 8' to abut at one end against the follower 7' I provide another follower 17, similar to the rear follower 6', which rests 70 against side stops 18 and is pressed against a stop 19, extending between the two legs of the yoke. Inasmuch as this stop 19 moves with the yoke, it will be evident that upon any movement of the draw-bar the spiral 75 springs 8' will be compressed the same distance that the follower 7' or 10' is moved. In this way the action of the friction-gear is aided by the resistance of the springs 8', thus increasing the power of the rigging as a whole, 80 while at the same time the easy action on lighter strains is provided for by allowing a space between one of the followers 7' and 10' and stops on the draft-iron. 85

When the parts are in the position shown in Fig. 2, it is evident that on a light pulling strain the springs 8' will be compressed without any action of the friction-gear until the follower 10' reaches the stops 15'. After this amount of movement both gears act together. 90

Instead of the form shown the spacer in the strap may be narrower than the side stops, so that a gap is made between the follower 7' and this spacing-block.

The advantages of my invention result 95 from combining the friction-gear having the spring-and-wedge system with an ordinary spring-gear arranged in tandem therewith, since I thereby obtain easy action for light loads, while providing power sufficient for 100 heavy loads. I am also enabled to make the degree of inclination of the wedge-spaces any

amount desired, according to the amount of movement or the capacity.

Many variations may be made in the form and arrangement of the spring-gears, the 5 wedge friction-gear, and the arrangements of the parts without departing from my invention.

I claim—

1. In a draft-rigging, a spring resistance in 10 combination with a friction-gear arranged in tandem therewith, the friction-gear containing a pair of blocks or followers having oppositely-inclined faces acting upon oppositely-moving wedge-blocks with a spring between them; substantially as described.

2. In a draft-rigging, a yoke with an intermediate spacing-block, a spring resistance on one side of the block and a friction-gear on the other side of the block and in tandem, 20 said friction-gear containing a pair of blocks

or followers having oppositely-inclined faces acting upon oppositely-moving wedge-blocks with a spring between them; substantially as described.

3. In a draft-rigging, a spring resistance in 25 combination with a friction-gear arranged in tandem therewith, the friction-gear containing a pair of blocks or followers having oppositely-inclined faces acting upon oppositely-moving wedge-blocks with a spring between them, and stops arranged to allow compression of the spring resistance before the friction-gear is brought into action; substantially as described.

In testimony whereof I have hereunto set my hand.

WILLIAM M. PIPER.
